MANUALLY OPERATED RESUSCITATOR
Lawrence N. Lea, 1683 University Ave., Bronx, N.Y.
Filed June 22, 1960, Ser. No. 37,871
9 Claims. (Cl. 128—29)

This invention concerns a manually operated resuscitator.

The technique of resuscitation of persons whose respiration has stopped, by means of mouth-to-mouth breathing, has proven effective in numerous emergency situations. However, the direct contact between the mouth of a person administering this form of resuscitation and the patient being revived is unsanitary and has many other obvious disadvantages. It has been proposed to provide first-aid workers with tubes of various types, one end of a tube being inserted in the mouth of the person administering resuscitation and the other end of the tube being inserted in the mouth of the person being revived. This avoids some of the objections to mouth-to-mouth breathing but is still disadvantageous, because air administered to the patient is oxidized to some extent, face-to-face disposition is required between patient and resuscitator, etc.

The present invention has an object avoidance of the above and other disadvantages and difficulties with such devices and the provision of an improved resuscitation device which is manually operated and requires no mouth-to-mouth connection.

A further object is provision of a device which is valve controlled for injection of air to the mouth of the patient and permitting free exhalation by the patient.

Another object according to one form of the invention is to provide a resuscitator device in which a manually operable bulb or bladder is connected to a removable sterilized mouth tube or nozzle, the bulb containing a resilient ball or balls for limiting compression of the bulb while administering air to a patient. This form is especially valuable in hospitals and institutions.

Still another object is provision of a resuscitation device of the character described with a two-way valve between the bulb and mouth tube for injecting fresh air orally under pressure into the mouth of the patient and permitting free exhalation by the patient, the device permitting the patient's body to be free and clear so that supplementary resuscitation processes such as artificial respiration by diaphragm manipulation can be performed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a side elevation view of a device embodying one form of the invention, parts being broken away.

FIG. 2 is a top plan view of the device.

FIG. 3 is a sectional view taken on line 3—3 of FIG. 2.

FIG. 4 is an exploded perspective view of components of the device.

FIG. 5 is an exploded perspective view on an enlarged scale of a valve core and spring employed in the device.

FIG. 6 is an edge view of a modified form of the invention in collapsed condition.

In FIGS. 1—4, there is shown a resuscitation device designed generally by numeral 10. The device is provided with a tubular nozzle 11 having a curved free end 12 adapted to be inserted into a patient's mouth. An oval or rectangular thin flat shield 13 is integrally formed with the tube and extends perpendicularly thereto near its other end 14. End 14 is formed as a nipple with an external thread 15. The nozzle 11 is preferably formed of

2

a plastic material which is stiffly flexible, such as polyethylene, vinyl, silicone rubber, and the like, but may be made of metal or any other suitable material. The material of the tube should be heat resistant and chemically inert so that it can be sterilized repeatedly by steam or immersion in suitable chemical germicides.

An air pump in the form of a bulb or bladder 16 is provided for forcing air through the nozzle 11. The bulb is formed of an outer resilient oval shell 17 and an inner resilient shell 18 of the same shape, leaving a space between the shells. The shells may be formed of plastic material or rubber. The outer shell 17 is sectional including an upper section 19 and a lower section 20 as viewed in FIG. 1. The sections are fused together at their free edges 21 and 22 to form a hermetically sealed joint 23. The inner shell 18 is similarly sectioned having an upper section 24 and a lower section 25 with their meeting edges sealed as indicated at 26.

Adjacent the apical end of outer shell 17, there is a nipple 27 provided with a removable closure pin 28. At the apical end of the outer shell, there is another nipple 29 in line with and receiving a similar nipple 30 in the apical end of the inner shell 18. A one-way valve 31 is fitted in the nipple 30 on the outer shell. Valve 31 includes an externally threaded cylindrical body 32 which has a bore 33 in which is slidably mounted a core 34. This core, as best shown in FIGS. 3 and 5, has a wider cylindrical portion 36 and a cylindrical portion 37 of reduced diameter formed with a plurality of longitudinal grooves 39 extending radially inward from the cylindrical surfaces of the core. The grooves terminate short of the circular lower end 38 of the core. This end of the core seats on a shoulder of a counterbore 42 formed in the body 32. The diameter of the core is less than the diameter of the counterbore so that when the core is lifted off the shoulder 40, air can pass freely through bore 33 and grooves 39 and into the inner shell 18 of the bulb via a passage 41 formed at the nipple 29 at the apical end of the shell 18.

40 A pin 44 is formed on the core. This pin extends through bore 33 and terminates in a head 44a secured thereto outside the shell. This pin can be manipulated manually if required.

45 Inside the inner shell 18 of the bulb 16 are elastic, sponge rubber balls 48, 50 which limit manual compression of the bulb when expelling air therefrom through the top end of shell 18. Projections 43 in shell 18 space ball 48 from opening 41.

Outer shell 17 has a nipple 49 formed at the apical 50 end thereof, adapted to receive a nipple 47 on the top end of shell 18. In nipple 49 there is securely and frictionally fitted an elbow end 54 of a connecting tube 50. Tube 50 is a rigid member having an internally threaded portion 52 at its other end. The thread 15 of nipple 14 55 engages in this threaded portion 52 as shown in FIGS. 1—3. A coil spring 56 having a diameter smaller than the bore 51 of the tube 50 expands and contracts axially in the tube between the annular end 53 of nipple 14 and a short cylindrical valve element 62 slidable in bore 51.

60 Opposed holes 55, 57 are provided in tube 50. The holes are normally held clear and uncovered by the extended spring 56. When the valve element 62 is moved to the left from its position as shown in FIG. 3, under air pressure, it compresses the spring and closes openings 55, 57. Element 62 is formed of flexible rubber or plastic material. It has a circular end wall 64 which is slit radially at 65 to form normally closed triangular flaps. These flaps separate under pressure of air ejected from bulb 16 to permit the air to pass through bore 68 in the element 62. A peripheral ridge 72 is formed in tube 59 near the elbow end to serve as a means for limiting

70

movement of element 62 while subject to expanding bias of spring 56.

A circumferential ridge 74 is formed at the exterior of shell section 19 and another similar ridge 76 is formed on shell section 20. These ridges are marked adjacently at 78 and 80 with indicia comprising instructions for the use of the device. The several components shown in FIG. 4 will be assembled as shown in FIGS. 1-3. The mouthpiece 11 is removable from the connecting tube 50 for sterilization before and after use.

It will be noted that ball 48 is larger and is located near the lower apical end of the bulb, while ball 50 is smaller and is located near the transverse plane of largest diameter. Ridge 76 is located between joints 29 and 26 and the lower end of the bulb.

In using the device, by a policeman in rescuing an infant for example, the pin 28 is removed from the nipple 27 and the nipple placed in the mouth and air forced into the space between the outer and inner shells 17 and 18, respectively, the air serving as a cushion. The head 44a of the pin 44 is then manually pressed inwardly opening the valve 31 permitting ambient air to enter into the inner shell 18 expanding said shell.

When the bulb is expanded with air, the user such as the policeman will manually press the lower sections 20 and 25 of the bulb when an infant is to be resuscitated with the device as advised by instructions 80. The large ball 50 will limit the compression of the bulb to pass only a small amount of air out of the bulb with each compression. The smaller ball located near upper ridge 74 will permit greater compression of the bulb to discharge more air such as required in resuscitating small children, as advised by instructions 78. In order to resuscitate older children and adults, the upper sections 19 and 24 of the bulb will be compressed at ridge 79 to discharge the largest volume of air at a time, as advised by instructions 82.

When the bulb 16 is compressed at any portion thereof, valve element 62 moves under air pressure in tube 50 to compress spring 49 and close holes 55, 57. Further pressure of air forces open the triangular flaps in walls 64 permitting the air to pass through passage 68 in element 62 and passage 15 in tube 11. Spring 56 is a rather light spring so that it yields first to permit member 62 to move and close holes 55, 57 before the flaps in walls 64 open to pass air therethrough. The curved end 12 of the nozzle 11 will be inserted in the mouth of the patient with shield 13 located between the teeth or gums and the lips of the patient. After bulb 16 is fully compressed and no more air is being discharged into tube 50, the flaps in walls 64 will close and spring 56 will expand to retract element 62 and clear and uncover holes 55, 57. The patient can then exhale freely through the cleared holes in the tube 50.

Valve 31 closes when the bulb is being compressed and expands due to its natural resilience to permit air to enter under suction through valve 31. Pin 44 is pushed into valve body 32 manually against the bias of spring 45 to lift core 34 off of the shoulder of the counterbore 42 and provide a passage for air through bores 33 and 42 into the bulb. When the pin is released, spring 45 expands to close the valve 31.

The device described can be readily disassembled for cleaning and sterilizing all components. It provides a regulated amount of air to each patient depending on his respiration requirements. Alternatively the user can progressively increase the amount of air discharged by changing the position of his hand on the bulb. If desired, the threaded end of valve 31 can be connected to an external pressurized source of oxygen or air.

In FIG. 6, a modified form a resuscitation device 10' is shown. This device 10' is similar to the resuscitation device 10 of FIG. 1 except that the balls 48 and 50 are omitted from inside the bulb or bladder 16' in order that the bulb or bladder may be completely collapsed to the condition shown in FIG. 6. In this condition, the de-

vice 10' may be inserted into pocket of the policeman or civil defense guard or readily placed in compact form in a small case.

While I have illustrated and described the preferred embodiments of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. A manually operable resuscitator device, comprising a nozzle having a curved end adapted for disposition in the mouth of a patient, a flexible compressible bulb provided with one-way valve means for passing fresh air into the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said openings, there being at least one compressible member in the bulb to limit compression thereof for controlling the amount of fresh air discharged from the bulb when compressed at said compressible member, said spring being sufficiently stiff to permit the flexible tubular member to move past the opposed openings before the flexible flaps are opened.

2. A manually operable resuscitator device, comprising a nozzle having a curved end adapted for disposition in the mouth of a patient, a flexible compressible bulb provided with one-way valve means for passing fresh air into the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said openings, there being at least one resilient ball in the bulb to limit compression thereof for controlling the amount of fresh air discharged from the bulb, said spring being sufficiently stiff to permit the flexible tubular member to move past the opposed openings before the flexible flaps are opened.

3. A manually operable resuscitator device, comprising a nozzle having a curved end adapted for disposition in the mouth of a patient, a flexible compressible bulb provided with one-way valve means for passing fresh air into the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said openings, there being at least one resilient ball in the bulb to limit compression thereof for controlling the amount of fresh air discharged from the bulb, said one-way valve means including a valve body having a

passage therethrough, a core normally held seated on a shoulder on a counterbore in the body by spring means closing said passage, said core having a pin extending out of said body for manual operation to move the core and open said passage, said spring being sufficiently stiff to permit the flexible tubular member to move past the opposed openings before the flexible flaps are opened.

4. A manually operable resuscitator device, comprising a nozzle having a curved end adapted for disposition in the mouth of a patient, a flexible compressible bulb composed of an outer shell and an inner shell spaced therefrom, a nipple on the outer shell for supplying air under pressure into the space between the outer and inner shells with one-way valve means for passing fresh air into the inner shell of the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said openings, there being a plurality of resilient balls in the bulb to limit compression thereof to different selective degrees for discharging predetermined amounts of fresh air from the bulb to the nozzle, said spring being sufficiently stiff to permit the flexible tubular member to move past the opposed openings before the flexible flaps are opened.

5. A manually operable resuscitator device, comprising a nozzle having a curved end adapted for disposition in the mouth of a patient, a flexible compressible bulb composed of an outer shell and an inner shell spaced therefrom, a nipple on the outer shell for supplying air under pressure into the space between the outer and inner shells with one-way valve means for passing fresh air into the inner shell of the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said openings, there being a plurality of resilient balls in the bulb to limit compression thereof to different selective degrees for discharging predetermined amounts of fresh air from the bulb to the nozzle, said one-way valve means including a valve body having a passage therethrough, a core normally held seated on a shoulder on a counterbore in the body by spring means closing said passage, said core having a pin extending out of said body for manual operation to move the core and open said passage, said spring being sufficiently stiff to permit the flexible tubular member to move past the opposed openings before the flexible flaps are opened.

6. A manually operable resuscitator device, comprising a nozzle having a curved end adapted for disposition in the mouth of a patient, a flexible compressible bulb provided with one-way valve means for passing fresh air into the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to

form flexible separable flaps, said tube having opposed openings normally disposed beyond the tubular member and adapted to be closed by said member when disposed thereat, and a spring normally retracting said member to clear said openings, said member being movable by pressure of air discharged from the bulb into the tube, said spring being sufficiently elastic to yield first so that the member moves to close said openings before the flaps in said wall separate to admit fresh air, and said flaps close upon release of said pressure before the spring retracts the tubular member from the openings in the tube, said spring being sufficiently stiff to permit the flexible tubular member to move past the opposed openings before the flexible flaps are opened.

15 7. A manually operable resuscitator device, comprising a nozzle having a curved end adapted for disposition in the mouth of a patient, a flexible compressible bulb provided with one-way valve means for passing fresh air into the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said openings, there being a plurality of resilient balls in the bulb to limit compression thereof to different selective degrees for discharging predetermined amounts of fresh air from the bulb to the nozzle, said one-way valve means including a valve body having a passage therethrough, a core normally held seated on a shoulder on a counterbore in the body by spring means closing said passage, said core having a pin extending out of said body for manual operation to move the core and open said passage, said member being movable by pressure of air discharged from the bulb into the tube, said spring being sufficiently elastic to yield first so that the member moves to close said openings before the flaps in said walls separate to admit fresh air, and said flaps close upon release of said pressure before the spring retracts the tubular member from the openings in the tube, said spring being sufficiently stiff to permit the flexible tubular member to move past the opposed openings before the flexible flaps are opened.

8. A manually operable resuscitator device, comprising a nozzle having a curved end adapted for disposition in the mouth of the patient, a flexible compressible bulb composed of an outer shell and an inner shell spaced therefrom, a nipple on the outer shell for supplying air under pressure into the space between the outer and inner shells with one-way valve means for passing fresh air into the inner shell of the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said opening, said spring being sufficiently stiff to permit the flexible tubular member to move past the opposed openings before the flexible flaps are opened.

9. A manually operable resuscitator device, comprising a nozzle having a curved end adapted for disposition in the mouth of a patient, a flexible compressible bulb provided with one-way valve means for passing fresh

air into the bulb, a tube detachably connecting the nozzle and bulb for passing fresh air from the bulb to the nozzle, and two-way valve means in the tube to pass fresh air to the nozzle and to divert exhaled air away from the bulb, said two-way valve means including a short flexible resilient tubular member slidably disposed in said tube, said member having normally closed end walls slit to form flexible separable flaps, said tube having opposed openings normally disposed beyond the tubular member and adapted to be closed by said member when disposed thereat, and a spring normally retracting said member to clear said opening, said one-way valve means including a valve body having a passage therethrough, a core normally held seated on a shoulder on a counterbore in the body by a spring means closing said passage, said core having a pin extending out of said body for manual operation to move the core and open said passage, said

member being movable by pressure of air discharged from the bulb into the tube, said spring being sufficiently elastic to yield first so that the member moves to close said openings before the flaps in said walls separate to admit fresh air, and said flaps close upon release of said pressure before the spring retracts the tubular member from the opening in the tube.
